US00D613352S

(12) **United States Design Patent**
Rangel

(10) **Patent No.:** **US D613,352 S**
(45) **Date of Patent:** **** Apr. 6, 2010**

(54) **PORTABLE RESISTANCE TRAINING DEVICE**

(76) Inventor: **Albert Rangel**, 1103 Beckman,
Houston, TX (US) 77076

(**) Term: **14 Years**

(21) Appl. No.: **29/313,814**

(22) Filed: **Feb. 13, 2009**

(51) **LOC (9) Cl. 21-02**

(52) **U.S. Cl. D21/692; D21/662**

(58) **Field of Classification Search D21/687,

(57) **CLAIM**

The ornamental design for a portable resistance training device.

DESCRIPTION

FIG. 1 is an isometric view for a portable resistance training device, as shown and described;

FIG. 2 is a front view thereof;

FIG. 3 is a rear view thereof;

FIG. 4 is a left side view with a right side view being the mirror image thereof;

FIG. 5 is a top view thereof; and,

FIG. 6 is a bottom view thereof.
